(57) **CLAIM**

The ornamental design for a thermostat with attachment for removable cover, as shown and described.

DESCRIPTION

FIG. 1 is a front elevation view of a thermostat with attachment for removable cover showing my new design with the cover installed.

FIG. 2 is a top plan view thereof. The bottom view is a mirror image of FIG. 2.

FIG. 3 is a right side elevation view thereof. The left side elevation is a mirror image of FIG. 3.

FIG. 4 is a perspective view thereof.

FIG. 5 is a front elevation view of a second embodiment of a thermostat with attachment for removable cover with the cover in a secondary position.

FIG. 6 is a top plan view of the second embodiment.

FIG. 7 is a bottom view of the second embodiment.

FIG. 8 is a right side elevation view of the second embodiment. The left side elevation view is a mirror image of FIG. 8.

FIG. 9 is a perspective view of the second embodiment.

FIG. 10 is a front elevation view of a third embodiment of a thermostat with attachment for removable cover.

FIG. 11 is a top plan view of the third embodiment.

FIG. 12 is a right side elevation view of the third embodiment. The left side elevation is a mirror image of FIG. 12.

FIG. 13 is a bottom view of the third embodiment; and,

FIG. 14 is a perspective view of the third embodiment.
